UNITED STATES PATENT OFFICE

RALPH L. JENNER, OF LE ROY, NEW YORK, ASSIGNOR TO LAPP INSULATOR COMPANY,
A CORPORATION OF NEW YORK

DEAD END CLAMP

Application filed July 29, 1930. Serial No. 471,557.

This invention relates to dead end clamps for securing guys, cables, conductors, or other tension members under proper conditions between the last horizontal support of the tension member and the ground anchor at which it finally ends.

The disadvantages of known dead end clamps are too well known to require discussion, but they particularly are defective as to rigidity of position, strain of clamp and tension member and ineffective grip upon the tension member.

One of the objects of my invention is the provision of a dead end clamp which obviates hitherto accepted defects and which possesses further advantages peculiar to its own construction.

Another object of the invention is the provision of a properly balanced and proportioned clamp made of a single forging and hence involving great strength without excessive material.

A further object of the invention is the provision of a clamp which progressively overcomes the tension on the tension member and which, at the same time, does not unduly set up undesired stresses and strains.

Other and further objects will be understood by those skilled in this art or will be apparent hereinafter.

In the accompanying drawings:

Figure 1 is a side elevational view of the assembled clamp, the clamp being turned upside-down for convenience.

Fig. 2 is a vertical medial section through Fig. 1.

Fig. 3 is a perspective view of the keeper member.

Fig. 4 is a view of the body member looking down upon the grooved side.

Fig. 5 is a view similar to Fig. 1 of a modified form.

Fig. 6 is a view of the body member of Fig. 5.

Fig. 7 is a perspective of the keeper member of Fig. 5; and

Fig. 8 is a section on the line VIII—VIII of Fig. 5.

Similar numerals indicate similar parts throughout the several views.

The dead end clamp of my invention consists generally of a body member 10 and a cooperating keeper member 11, both being preferably made of forged metal to give maximum strength with a minimum of material.

The body member 10 is somewhat L-shaped, although the construction, as shown, is not a right-angled one and hence for convenience the body will be hereinafter referred to as an angled body member. As shown, the body member has a straight body portion provided with a groove 12 between side walls 13, the groove tapering as shown in Fig. 4 for a purpose to be pointed out hereinafter.

The body member merges or curves into the angled portion 14, which in use is at the top and substantially horizontal when in operative position, so that the groove 15 in this angled member is substantially horizontal and faces upwardly. An aperture 16 is provided as shown through each side wall of the groove for the purpose of connecting the clamp to a suitable support or insulator (not shown) and in use a suitable tie rod (not shown) is utilized to make the connection.

Extending laterally from the side walls of the groove are a plurality of apertured ears 17 unitarily forged with the side walls. The floor or bottom of the groove is, moreover, waved or corrugated as shown at 18, Fig. 2, the purpose of which will be understood hereinafter. The extreme ends of the body member are flared or curved at 19, to prevent a sharp edge or a rapid change in curvature from coming into contact with the cable, with a consequent high stress at this point. The taper of the groove is also so adjusted that the tension member is gripped more and more tightly the nearer it gets to the land anchor to which it is eventually secured.

The keeper member as shown particularly in Fig. 3 has a relatively long and narrow body portion 20 with reinforced or strengthened portions 21 and cut away or lightened additional portions 22. The underside of the body portion is waved or corrugated at 23, but as will be apparent from Fig. 2 particularly, the corrugations of the keeper are opposite to those of the body member, that is,

a prominence of the floor or groove of the body member is opposite a depression or trough in the under-surface of the keeper member and accordingly a trough in the floor 5 of the body member is opposite a prominence in the under-surface of the keeper member. It will be apparent that such a construction forces the cable or tension member to take a sinuous or tortuous path through the 10 assembled body and keeper members and this particularly in conjunction with the tapering groove, or throat, as it may be called, provides an arrangement which is particularly effective both in gripping the cable or tension member and in holding it firmly in position. The taper of the groove, as has been 15 explained, causes the tension member to be gripped more and more tightly, therefore, relieving it more and more of its load, so that near the exit end of the clamp the load on the 20 tension member is practically zero and the grip of the clamp is the tightest so that unusually efficient clamping action is secured without undue strain on the cable strands.

It will be seen that a number of bolts 24 25 exteriorly threaded at 25 and each provided with a guide tip 26 extend from the straightened or reinforced portions of the keeper body and it is apparent that the number of bolts which are forged unitarily with the keeper body is equal to the number of apertured ears which are also unitarily forged and each of which is adapted to receive a bolt as shown in the assembled view of Fig. 30 1. Nuts 27 are screwed up on the bolt members so as to clamp the keeper and body members together in operative association and the guide tips above mentioned enable the nuts to be quickly and easily threaded on the bolts 35 when the clamp is being assembled in position. To facilitate the threading of the nuts a counter-sink (not shown) may be provided in the flat side of the nut so that whether or not the nut is presented to the bolt at exactly 40 the right angle to catch the thread will be immaterial.

In the modified form of Figs. 5 to 8, inclusive, the main features and considerations are the same as those considered aenent Figs. 50 1 to 4, inclusive, except that in Figs. 5 to 8, inclusive, the body member 10' has the unitary forged bolt construction 21', 24' and 26' as will be clearly understood from the foregoing and the keeper member 11' has 55 the apertured ear construction 17'.

In either case, the cable is embraced entirely, the wire being seated in a groove with side faces, both of which are pierced by hole 16 in order to attach the clamp to an adapter. 60 This is a great advantage over the offset or side opening type of groove wherein the edges are not extended and pierced by a hole for attachment but wherein attachment is made to one extended edge which must be 65 extremely heavy, due to the fact that it must

withstand stresses like those existing in a hook in contradistinction to the present invention in which the stresses are divided in the two faces as in a shackle or clevis.

The hole 16 aforesaid is near the center of 70 mass of the clamp and indisputable advantages are thereby obtained. The depth of the clamp being relatively small, also, the parts can be unitarily forged which would be impossible in a clamp of considerable depth. 75

If desired, a lock washer arrangement may be incorporated and as shown in Fig. 1 the flat side of the nut is provided with a number of serrations 28 and as a matter of fact and convenience, these serrations are automatically placed on the nut surface by the use of a properly shaped die when the nuts are punched out so that the provision of the serrations adds no expense whatever to the manufacture of the nuts. Similarly, serrations 29 may be placed on the proper surface of the apertured ears 17, so that by the interposition of a washer 30 an efficient locking arrangement is secured as the ends of the washer, which may be provided with a slight 90 extension, if desired, catch in the serrations and prevent loosening of the nut, which may, however, be removed, if necessary, by the application of considerable force, in which case, the serrations of the nut may be stripped, but 95 a new nut can be readily used without much expense or the washer itself may open out. This is a great advantage over prior constructions wherein the clamping pressure was lost and the wire slipped. 100

In use the clamp is arranged so that the last horizontal portion of the tension member is received in the groove of the angled portion of the guide which, thereafter points toward the ground at an angle of about 60 105 degrees, the tension member emerging from the lower end of the clamp, shown at the top of Figs. 1 and 2, and then passing in any suitable way to a land anchor. An important function and use is in "dead-ending" a conductor, transmission cable or wire. 110

What I claim as new and desire to secure by Letters Patent is:

1. A dead-end clamp comprising an angled body member adapted to receive a cable, said body member having a tapered throat portion to grip said cable progressively more tightly and having a wavy floor, a keeper member constructed to co-operate with said body member, and means for securing said members in operative association. 115

2. A dead-end clamp comprising an angled body member adapted to receive a cable, said body member having a tapering throat to grip said cable progressively more tightly 120 and having a wavy floor, a keeper member constructed to co-operate with said body member and having a wavy under-surface, and means for securing and locking said members in operative association. 125

3. A dead-end clamp comprising an angled body member adapted to receive a cable, said body member having a tapering throat to receive and grip said cable progressively more tightly and having a wavy floor, a keeper member constructed to co-operate with said body member and having an oppositely waved under-surface, said keeper member having parts cut away for lightness and other parts reinforced, guide-tipped bolts extending unitarily from said reinforced parts, aperture ears on said body member for receiving said bolts, and means for securing and locking said members in operative association.

4. In a dead-end clamp, a body member having unitary forged bolts and a coextensive keeper member with the bolt-carrying part of the body member having unitary forged apertured ears to receive said bolts, said body member having a longitudinal groove, the walls of which have an aperture substantially adjacent the center of mass of the clamp, said groove being tapered and having a wavy floor and said keeper member having a cooperating wavy surface.

5. A dead end clamp comprising a generally L-shaped body member provided with a cable receiving groove, and a single keeper member coextensive with a major part of said body member, said body member and keeper having interengaging bolt and ear elements unitarily forged therewith, said groove having its walls and floor and said keeper member having its under surface configured for progressive clamping effect.

6. An L-shaped dead-end clamp comprising a leg and a foot portion arranged to meet at an angle of less than 180°, said leg portion being provided with unitary forged bolts and a keeper member, substantially coextensive with said leg portion only, provided with unitary, forged apertured ears to receive said bolts, said clamp being grooved and the groove walls being transversely apertured substantially at the center of mass of the clamp, the apertures lying at the heel of said clamp.

In testimony whereof, I have hereunto subscribed my name this 25th day of July, 1930.
RALPH L. JENNER.
